UNITED STATES PATENT OFFICE.

HENRY KRUESHELD, OF MANSFIELD, OHIO, ASSIGNOR TO WESTINGHOUSE ELECTRIC PRODUCTS COMPANY, A CORPORATION OF MICHIGAN.

STAND FOR TRAVELER'S IRON.

Application filed January 20, 1920. Serial No. 352,717.

To all whom it may concern:

Be it known that I, HENRY KRUESHELD, a citizen of the United States, and a resident of Mansfield, in the county of Richland and State of Ohio, have invented a new and useful Improvement in Stands for Traveler's Iron, of which the following is a specification.

My invention relates to electrically-heated apparatus and particularly to supporting means for electric sad irons.

The object of my invention is to provide simple and novel means for supporting an electric sad-iron in an inverted position, so that the iron may be used for cooking or for heating purposes.

More specifically, my invention embodies a plurality of plates which form a stand for supporting a sad iron in its normal upright position and which I provide with a plurality of spaced and longitudinally aligned spring members, of substantially U-shape, mounted on one of said plates for engaging the handle member of a sad iron and holding it in an inverted position on the stand.

Referring to the single sheet of drawings, Figure 1 is a side elevation of the device embodying my invention, as applied to a sad-iron stand and operatively associated with an electrically heated sad iron to hold the same in an inverted position on the stand; Fig. 2 is a top plan view of the device embodying my invention, with the supporting frames in inoperative position, and Fig. 3 is a top plan view of the spring-supporting members in operative position on a stand.

A sad-iron stand 1 comprises a plurality of parallel plates 3 and 4 of the same contour as the sad iron 2 and an intermediate plate 5, each of the plates 3 and 4 being provided with a plurality of similarly aligned and co-operating integral curved portions 6. The stand 1 is more fully described and claimed in an application, Serial No. 129,270, filed by Frank Thornton, jr., under date of Nov. 3, 1916, and assigned to the Westinghouse Electric & Manufacturing Company and will not be further described in detail here.

The sad iron 2, being fully described and claimed in a co-pending application Serial No. 349,286, filed by me under date of Jan.

3, 1920, no detailed description thereof will be given here.

The means for holding the sad iron 2 in an inverted position comprises a plurality of wire frames 7 and 8, each of substantially U-shape, which are pivotally mounted on the plate 3. As the members 7 and 8 are substantially alike, in all respects except size and are oppositely bent so as to engage opposite ends of the sad-iron handle member, only one will be fully described.

As shown best in Fig. 3, the central part of the member 7 comprises a horizontal straight portion 9 connected to two integral parts 10 of U-shape, the length of the portion 9 being made substantially equal to the width of the supporting strap 11 of the sad-iron handle. The side portions 12 are integral with the portions 9 and 10 and are bent at right angles to the part 9 and parallel to each other. A short integral end portion 13 is bent at right angles to one of the side portions 12 and another short integral end portion 14 of substantially L-shape is bent at right angles to the other side portion 12. The two end portions 13 and 14 are pivotally mounted in sockets 15 and 16 which are formed in the plate 3 by pressing relatively small parts of the same upwardly above the surface of the plate, as shown in Fig. 1. A depression 17 is provided in each of the rear curved portions 6 to receive the U-shaped portions 10 of the member 7 when it is in its inoperative position, as shown in Fig. 2. Two small notches 18 are provided at the inner edges of a substantially triangular opening 19 in the plate 3, to receive the portions 10 of the member 9 when it is in its inoperative position, as shown in Fig. 2.

When the members 7 and 8 are in the position shown in Fig. 2, the sad iron stand 1 may be used to support the sad iron 2 in its normal upright position. In order to support the sad iron 2 in an inverted position on the stand 1, the members 7 and 8 are so moved as to extend at substantially right angles to the surface of the plate 3, as shown in Fig. 1. It may be noted, by reference to Fig. 3, that the L-shaped extension 14 on each of the members 7 and 8 acts as a means for preventing further pivotal movement of these members away from each other. The sad iron 2 may now be placed in

an inverted position between the members 7 and 8 which will resiliently engage the strap 11 and hold the sad iron in its inverted position, the handle member 20 of the iron 2 resting in the slot 19 and engaging the edges of the plate 3 near the ends of the slot. The member 7 is made shorter than the member 8 in order to avoid interference with the terminal socket 21 mounted at the rear of the iron 2.

I thus provide relatively simple and novel means for co-operating with an electric sad iron to support it in an inverted position on a sad-iron stand, which means may be quickly placed in an inoperative position on said stand where it will not interfere with the use of the sad iron stand for supporting the sad iron in its normal upright position.

Various changes may be made in the device without departing from the spirit and the scope of my invention, and I desire that only such limitations shall be placed thereon as are imposed by the prior art or are specifically set forth in the appended claims.

25 I claim as my invention:

1. The combination with a stand adapted to support a sad iron in normal upright position, of a plurality of members of substantially U-shape pivotally mounted on said stand for holding the iron in an inverted position on the stand.

2. The combination with a stand adapted to support a sad iron having a handle member, in normal upright position on said stand, of a plurality of members of substantially U-shape pivotally mounted on said stand and adapted to operatively engage the handle member of said sad iron for holding the iron in its inverted supported position on said stand.

3. A supporting means for a sad iron having a handle member and a handle supporting strap of substantially U-shape, comprising a stand for supporting said iron when the same is placed in an upright position on said stand, a plurality of resilient members of substantially U-shape pivotally mounted on said stand and adapted to operatively engage the supporting strap and maintain the same in a vertical position

when the sad iron is placed on said stand in an inverted position.

4. A supporting means for a sad iron having a body member, a handle member and a handle-supporting strap of substantially U-shape, comprising a plurality of parallel-extending plates and a plurality of resilient members of substantially U-shape pivotally mounted on one of said plates and adapted to extend parallel to said plates and toward each other when the iron is supported in its normal upright position on said plates and to extend approximately parallel to each other and at right angles to said plates and operatively engage said supporting strap and thereby hold said iron in an inverted position on said plates.

5. A stand for supporting a sad iron having a handle strap, said stand having means for holding said iron in an inverted position on said stand, said holding means comprising a pair of resilient wire frames, of substantially U-shape and of different lengths, pivotally mounted on said stand for operatively engaging said supporting strap at the front and the rear ends of the iron.

6. The combination with a sad-iron stand adapted to support a said iron in normal upright position, of a plurality of wire frames of substantially U-shape pivotally mounted in spaced relation on said frame and adapted to extend parallel to said stand when the iron is supported in its normal position thereon and to extend approximately at right angles to said stand to maintain said sad iron in inverted position thereon.

7. The combination with a flat-iron comprising a body member and a handle member, of means for supporting said iron in its normal upright position, and means pivotally mounted on said supporting means for maintaining the iron in an inverted position on said supporting means with the handle member operatively engaging said supporting means.

In testimony whereof, I have hereunto subscribed my name this 30 day of Dec. 1919.

HENRY KRUESHELD.
